[57] ABSTRACT

A diagnostic test package for use in an improved semi-quantitative method for estimating antitrypsin levels in human blood.

11 Claims, No Drawings

MASS SCREENING TEST FOR SERUM TRYPSIN INHIBITORS

BACKGROUND OF THE INVENTION

The association between pulmonary emphysema and α_1 -antitrypsin deficiency was first described in 1963 (Laurell, C.P. and Eriksson, S., *J. Clin. & Lab. Investigation*, 15, 132-140). They observed the almost invariable presence of severe pulmonary emphysema in persons over 40 years of age who were homozygous for this inherited plasma protein defect. Individuals homozygous for the genetic defect possess approximately 10 percent of the normal level of serum α_1 -antitrypsin; heterozygous individuals possess about 50 to 60 percent of the normal concentration of this protein.

As in other genetic entities, the degree of clinical manifestation in α_1 -antitrypsin deficiency is highly variable, ranging from complete absence of clinical symptoms to an early onset of severe emphysema with pronounced disability. But the homozygotes run greater risk of lung disease than the heterozygotes. The high risk of developing emphysema is increased with the cigarette smokers in this population.

Methods currently available for estimating antitrypsin levels in serum include enzymologic procedures involving the inhibition of digestion of protein substrates such as casein, fibrinogen and hemoglobin, and inhibition of hydrolysis of synthetic substrates such as benzoyl-L-arginine p-nitroanilide and p-toluene sulfonyl-L-arginine methyl ester. However, a rapid and simple procedure is needed for the semi-quantitative measurement of antitryptic activity in human sera, a procedure which would make possible the screening of large populations for the genetically controlled α_1 -antitrypsin deficiency that is associated with an unusual familial variety of pulmonary emphysema. Such information would be a valuable guide for premarital testing and counseling that could prevent the unfortunate births of homozygotes with a high probability of future crippling emphysema. Such information would also serve as a precautionary screening in employment examinations in industries with high exposure to irritating fumes, dusts or excessive smog. A background would be available for medical advice on the dangers of cigarette smoking.

A semi-quantitative test reported by James, K., Collins, M.L. and Fudenberg, H.H., *J. Lab. and Clin. Med.* 67, 528 (1966) measures the ability of antitrypsin containing serum to inhibit the capacity of reference trypsin standards to digest the gelatin surface of an unexposed and developed (black) X-ray film. The titration procedure involves the use of three concentrations of trypsin for each serum sample.

The object of this invention is to provide a rapid semi-quantitative procedure for determining antitrypsin levels in human sera in which one set of control sera serves as a reference for the mass screening of many individual human sera.

SUMMARY OF THE INVENTION

This invention is concerned with a diagnostic test package for use in an improved semi-quantitative method for estimating antitrypsin levels in human blood. The diagnostic test package contains a strip of unexposed and developed color film, sample test vials (each containing a constant amount of freeze-dried

trypsin for individual serum sample determinations when properly diluted with serum), and three reference vials (each containing a different amount of freeze-dried trypsin which serve as reference control sera when properly diluted with buffer). Antitrypsin levels in human sera are determined by the color changes resulting from the hydrolysis of the gelatin substrate of color film by the serum + trypsin reagent with side by side comparisons of the color changes produced by simulated normal, heterozygous and homozygous sera.

DETAILED DESCRIPTION OF THE INVENTION

The test method of this invention utilizes the depth of hydrolysis (with resultant color changes) into the tri-layered/tri-colored gelatin sandwich of an unexposed and developed color film strip as the semi-quantitative measure of the trypsin inhibitory capacity of human sera. Side by side comparisons are made with simulated normal, heterozygous and homozygous antitrypsin sera.

The test sera (0.2 ml.) are each added to individual vials containing 0.30 mg. of freeze-dried trypsin and mixed until all the trypsin has dissolved. After about 5 minutes incubation at room temperature, a drop (0.01-0.03 ml.) of each mixture is placed on the gelatin side of an unexposed and developed color film strip (any positive color film may be used, preferably Agfa-chrome). After approximately 5 minutes, the film strip is immersed in a pH 3 water rinse bath which stops the gelatin hydrolysis reaction. The film strip is gently rubbed or squeegeed until colored particles no longer are leached from the spotted area (approximately 30 seconds). The film strip is then removed from the bath, dried and the colored spots compared with those obtained from the five minute hydrolysis action of a drop (0.01-0.03 ml.) of each of the simulated normal, heterozygous and homozygous sera (prepared in an identical manner as the test sera, i.e., 0.2 ml. of (0.05-0.10 M) tris, (0.005-0.02 M) CaCl_2 , pH 8 buffer solution added to each of three individual vials containing respectively 0.06 mg., 0.18 mg. and 0.26 mg. of the same lot of freeze-dried trypsin). A light aqua-blue colored spot is obtained with homozygous α_1 -antitrypsin human sera and the corresponding simulated homozygous control. A blue-violet spot results from the action of heterozygous α_1 -antitrypsin sera and the corresponding heterozygous control. Normal α_1 -antitrypsin sera and the simulated normal control react very little on the gelatin substrate of the color film under the conditions of the test, and the color of the spot on the film is black (film unchanged) to black-violet. The test sera are reported as "normal," "heterozygous" or "homozygous."

The trypsin reagent vials (containing 0.30 mg. freeze-dried trypsin) are prepared by making up a 3.0 mg/ml. stock solution of twice-crystallized trypsin (Worthington Biochemicals or other suitable supplier) in pH 5-7 distilled water. Into each sample test vial (reagent vial) is deposited 0.10 ml. of this stock solution immediately followed by low temperature freeze-drying.

Reference samples of normal, heterozygous and homozygous α_1 -antitrypsin sera are simulated by the simple means of preparing trypsin stock solutions in pH 5-7 distilled water (using the same lot of trypsin as was

used in the filling of the sample test vials). 0.10 ml. of these 0.6 mg., 1.8 mg. and 2.6 mg/ml. reference stock solutions is deposited into the normal, heterozygous and homozygous reference control vials respectively, and each is freeze-dried. The rationalization for the reference controls is given in the following protocol:

1. A vial containing 0.3 mg/ml ($\pm 10\%$) trypsin [the normal reference control serum],
2. a vial containing 0.9 mg/ml ($\pm 10\%$) trypsin [the heterozygous reference control serum],
3. a vial containing 1.3 mg/ml ($\pm 10\%$) trypsin [the homozygous reference control serum] and

THREE CLASSES OF HYPOTHETICAL TEST SERA

Deficient state of serum	Mean T.I.C. *, mg./ml.	Mass of trypsin which 0.2 ml. of serum can inhibit, mg.	Mass of trypsin reagent to which 0.2 ml. of serum is added **, mg.	Residual or free mass of trypsin in the serum-trypsin reaction mixture, mg.	Residual concentration of trypsin in the serum-trypsin reaction mixture, mg./ml.	Mass of free trypsin in 0.02 ml. of serum-trypsin mixture applied to film, mg.
Normal	1.2	0.24	0.30	0.06	0.3	0.007
Heterozygous	0.6	0.12	0.30	0.18	0.9	0.018
Homozygous	0.2	0.04	0.30	0.26	1.3	0.026

* The mean trypsin inhibitory capacity (T.I.C.), expressed as mg. of trypsin capable of being inhibited by antitrypsin, taken from the literature for normal, heterozygous and homozygous α_1 -antitrypsin deficiency.

** The trypsin reagent has purposely been made more concentrated than the actual trypsin reagent, concentration necessary to titrate exactly the mean normal T.I.C. of 1.2 mg./ml. This use of a slightly higher trypsin reagent concentration is used to reduce the possibility of false negatives.

THE THREE SIMULATED REFERENCE CONTROLS

Deficient state of reference	Volume of pH 8 buffer added to reference vial, ml.	Mass of trypsin in reference vial, mg.	Concentration of trypsin in reference vial after addition of buffer***, mg./ml.	Mass of trypsin in 0.02 ml. of reference solution applied to film, mg.
Normal	0.2	0.06	0.3	0.006
Heterozygous	0.2	0.18	0.3	0.018
Homozygous	0.2	0.26	1.3	0.026

*** $\pm 10\%$.

What is claimed is:

1. In a diagnostic test procedure for the determination of α_1 -antitrypsin levels in human blood by commingling test sera with freeze-dried trypsin reagent and estimating the degree of hydrolysis of gelatin by the residual trypsin (free trypsin) into the surface of unexposed and developed photographic film, the improvement which comprises using unexposed and developed color film, producing color changes having colored end results into said surface by contacting said surface with sera-trypsin reaction mixtures and simulated normal, heterozygous and homozygous reference sera, and comparing the ultimate colors produced by said sera-trypsin reaction mixtures with the ultimate colors produced by said simulated normal, heterozygous and homozygous reference sera.

2. A diagnostic test procedure as set forth in claim 1, wherein a strip of unexposed and developed color film and the following bottled reagent are utilized:

A. freeze-dried trypsin of variable mass to provide on reconstitution with 0.2 ml. of pH 8 buffer:

B. freeze-dried trypsin test vials each containing 0.30 mg. of trypsin, and

C. 5.0 ml of (0.05-0.10 M) tris, (0.005-0.02 M) CaCl_2 , pH 8 buffer solution.

3. In a diagnostic test procedure as set forth in claim 2 wherein said strip of color film is a positive color film.

4. In a diagnostic test procedure as set forth in claim 1 wherein said color film includes three layers having different colorations and said color changes are produced as a result of the depth of hydrolysis by said residual trypsin.

5. In a diagnostic test procedure as set forth in claim 4 wherein said color film is a positive color film.

6. In a diagnostic procedure as set forth in claim 4 wherein a small amount of said mixture is applied to said color film and the time of contact being limited so that said colored end results occur.

7. In a diagnostic procedure as set forth in claim 6 wherein said color film to which said mixture is applied is washed after a predetermined time.

8. In a diagnostic procedure as set forth in claim 7 wherein said washed film strip is dried.

9. In a diagnostic procedure as set forth in claim 7 wherein said film strip is washed in a pH3 water rinse bath.

10. In a diagnostic procedure as set forth in claim 6 wherein said time of contact is about 5 minutes at about room temperature.

11. In a diagnostic procedure as set forth in claim 10 wherein a drop of said mixture is applied.
